AUTOMATIC DOOR BOTTOM

William E. Balousek, Hinsdale, Ill., assignor to
W. J. Dennis & Company, Chicago, Ill., a cor-
poration of Illinois

Application March 19, 1934, Serial No. 716,290

7 Claims. (Cl. 20—68)

This invention relates to closures, and particularly to an automatically actuated bottom for doors and the like.

One object of the present invention is to provide an automatically actuated door bottom wherein a weather strip is moved into operative position to close a crack or space beneath a door when the door is closed, and wherein the strip is automatically raised out of operative position when the door is opened.

Another object of the invention is to provide a structure of the character described wherein the weather strip is moved into effective engagement with a door sill whether positioned parallel with the bottom of the door or at an angle with respect thereto.

Another object of the invention is to provide a weather strip supporting and actuating assembly which is self-contained and which may be readily positioned and conveniently secured as a unit in a housing and door.

Another object of the invention is to provide a structure wherein all the movements of the weather strip are positively controlled by the mechanism employed in its operation.

Another object of the invention is to provide a structure wherein, any lost motion of the strip actuating mechanism and door, beyond the movement necessary to lower the weather strip into effective operative position, is automatically taken up.

A further object of the invention is to provide a structure wherein the means engageable with the actuating mechanism for lowering the weather strip to operative position, may be adjusted to vary the movement of the strip in accordance with the space between the bottom of the door and the door sill.

A still further object of the present invention is to improve devices of the character described in sundry details hereinafter referred to and particularly pointed out in the appended claims.

One embodiment of the present invention is shown for illustrative purposes in the accompanying drawing, in which

Fig. 1 is a fragmentary elevational view partly in section of a door illustrating the application of my improved automatic door bottom thereto, and showing the weather strip in raised position;

Fig. 2 is a view similar to Fig. 1 illustrating the various elements constituting the invention in changed position, and showing the weather strip in engagement with a door sill positioned at an angle to the lower edge of the door;

Fig. 3 is an enlarged transverse sectional elevational view taken substantially as indicated by the line 3—3 of Fig. 2; and

Fig. 4 is an enlarged fragmentary sectional plan view taken substantially as indicated by the line 4—4 of Fig. 1.

In the drawing, the illustrative embodiment of the invention is shown as mounted in the lower edge portion of a door 6, and comprises, in the present instance, an inverted channel or U-shaped housing 7 positioned in a groove 8 formed in the lower edge of the door and secured thereto by nails 9 or other suitable means as clearly shown in Fig. 3.

Slidably mounted in the housing 7 is an actuating member indicated, as a whole, by the numeral 11, and comprising a push rod 12 adapted to extend outside the housing, and an actuating plate 13 rigidly secured to the rod by means of bolts 14, the plate 13 being provided with longitudinally extending, preferably aligned, slots 15 and 16 adapted to receive, respectively, pivot pins 17 and 18 rigidly mounted in one wall of the housing 7, as clearly shown in Fig. 3, in a manner to provide guides for the actuating member 11.

Pivottally mounted on the pivot pins 17 and 18, at one side of the actuating plate 13, are oppositely extending arms 19 and 21 having crank pins 22 and 23 mounted, respectively, therein by which the said arms are pivotally connected to the plate 13 of the actuating member 11, the crank pin 22 of the arm 19 being positioned below the pivot pin 17 and the crank pin 23 of the arm 21 being positioned above the pivot pin 18, the arrangement being such that when the actuating member 11 and its plate 13 are moved in one direction or another the arms 19 and 21 will be rotated in opposite directions about the pins 17 and 18.

Pivottally mounted at the free end of the arm 21, by means of a stud 24, is a weather strip supporting bar 25 having a weather strip 26 formed, preferably, of fibrous or felt-like material, and holder 27 therefore secured to the bar 25 by means of screws 28, and formed in the bar 25 in spaced relation to the stud 24, is a slot 29 adapted to slidably receive a pin 31 mounted in the free end of the arm 19 and by which the bar 25 and arm 19 are connected.

Operatively related to the arms 19 and 21, and shown in the present instance as connected thereto above the pivot pins 17 and 18, is a tension spring 32 acting to lift and maintain the weather strip in its raised position within the housing 7.

The door 6 is shown, in the present instance, as hingedly connected to a door frame 33, and for acting upon the rod 12 to lower the weather strip 26 into engagement with the door sill 34 when the door is closed, a pressure member or stop indicated as a whole by the numeral 35 and having a concave face 36 formed thereon (Fig. 4) is shown as slidably mounted in a cup-like casing 37 positioned in a recess 38 formed in the door frame 33, the casing 37 having an opening 39 formed in its bottom portion adapted to receive a screw-threaded shank portion 41 formed on the pressure member 35. Positioned within the casing 37 between the bottom thereof and the inner side of the pressure member 35 is a spring 42 adapted to urge the pressure member in one direction and permitting it to yield and move inwardly in the opposite direction, the shank portion 41 being provided with nuts 43 cooperable with the bottom portion of the casing for limiting the outward movement of the pressure member 35, and for adjusting the pressure member 35 with respect to the casing, the member 35 is provided with a screw-driver slot 44 by which the shank portion 41 may be held against rotation while adjusting the nuts 43 thereon.

For removing the casing 37 from the recess 38 to make any desired adjustments of the pressure member with respect to the casing, the casing 37 may be provided with oppositely disposed apertures 45 formed in its wall portion and adapted to receive a suitable tool by which the casing may be withdrawn from the recess 38.

By reference to Fig. 1 it will be noted that the door 6 is partially open and that the protruding outer end of the push rod 12 of the actuating member 11 is out of engagement with the stop or pressure member 35, in which position of the actuating member including the rod 12 and the plate 13, the free ends of the arms 19 and 21, are held in their raised positions by means of the spring 32 with the weather strip 26 elevated and supported in its raised position within the housing 7, while in Fig. 2, the door 6 is shown in closed position with the rod 12 in engagement with the stop or pressure member 35 by which the actuating member 11 has been moved to the right, and through its crank pin connections 22 and 23 with the arms 19 and 21, respectively, has caused the arms to be rotated in opposite directions in a manner to move the free ends thereof downwardly, and the weather strip 26 into engagement with the door sill 34, which, in Fig. 2, is shown at an angle to the lower edge of the door, but it will be noted that by reason of the slot and pin connections 29-31 between the bar 25 and arm 19, the weather strip 26 has been moved into engagement throughout its length with the door sill 34.

It will be noted also that by reason of the yieldability of the stop or pressure member 35 as illustrated in Fig. 4, that after the weather strip 26 has been moved into efficient engagement with the door sill, any further or lost motion of the actuating mechanism and door in the closing thereof, will be taken up by the resiliency and yielding of the spring 42, thereby avoiding the necessity of closely adjusting the position of the pressure member or stop 35, but if for any reason an adjustment of the pressure member 35 with reference to the casing 37 should be desirable, it may be accomplished by means of nuts 33. It will be observed also that the concave face 36 of the pressure member 35 will act to center the push

rod 12 with respect thereto as it is brought into engagement therewith.

Obviously, the present invention is not limited to the precise construction and an arrangement shown and described as the same may be variously modified. Moreover, all the features of the invention need not be used conjointly as the same may be used to advantage in variously different combinations and subcombinations.

What I claim as new and desire to cover by 10 Letters Patent, is:

1. In an automatic door bottom, the combination of a housing adapted to be mounted in a door operatively related to a door frame, an actuating member longitudinally movable in said housing and comprising a push rod and a plate having a plurality of slots formed therein rigidly connected to said rod, a plurality of pivot pins mounted in said housing and extending respectively through said slots to provide guides for said actuating member, a plurality of arms pivotally mounted on said pins, crank pins for pivotally connecting the respective arms to said plate, a weather strip, a supporting bar therefor pivotally connected to the free end of one of said arms, said bar having a slot formed therein in spaced relation to the pivotal connection of the bar with said one of the arms, a pin mounted in the free end of the other of said arms and adapted to slidably engage the slot in said bar for connecting said other arm thereto, an adjustable stop in said door frame engageable with said rod for moving the actuating member in one direction in a manner to rotate said arms in opposite directions about said pivot pins to lower said weather strip as the door is being closed, and resilient means connected adjacent its ends to the respective arms for rotating them in the reverse directions to lift the weather strip and move said actuating member in the opposite direction as the door is being opened.

2. In an automatic door bottom, the combination of a housing adapted to be mounted in a door operatively related to a door frame, an actuating member longitudinally movable in said housing and comprising a push rod and a plate having a plurality of slots formed therein rigidly connected to said rod, a plurality of pivot pins mounted rigidly in said housing and extending loosely through the respective slots to provide guides for said actuating member, a plurality of arms pivotally mounted on said pins and extending, respectively, in opposite directions therefrom, crank pins below and above the respective pivot pins for pivotally connecting the respective arms to said plate, a weather strip, a supporting bar therefor pivotally connected to the free end of one of said arms, said bar having a slot formed therein in spaced relation to the pivotal connection of the bar with said one of the arms, a pin mounted in the free end of the other of said arms and adapted to slidably engage the slot in said bar for connecting said other arm thereto, a yieldable stop in said door frame engageable with said rod for moving the actuating member in one direction in a manner to rotate said arms in opposite directions about the respective pivot pins to lower said weather strip as the door is being closed, and resilient means directly connected adjacent its ends to the respective arms for rotating them in the reverse direction to lift the weather strip and move said actuating member in the opposite direction as the door is being opened.

3. In an automatic door bottom, the combi- 75

nation of a housing adapted to be mounted in a door operatively related to a door frame, an actuating member longitudinally movable in said housing and comprising a push rod and a plate 5 having a pair of slots formed therein rigidly connected to said rod, a pair of pivot pins mounted rigidly in said housing and extending loosely through the respective slots to provide guides for said actuating member, a plurality of 10 arms pivotally mounted on said pins and extending, respectively, in opposite directions therefrom, crank pins below and above the respective pivot pins for pivotally connecting the respective arms to said plate, a weather strip, a supporting bar 15 therefor pivotally connected to the free end of one of said arms, said bar having a slot formed therein in spaced relation to the pivotal connection of the bar with said one of the arms, a pin mounted in the free end of the other of said 20 arms and adapted to slidably engage the slot in said bar for connecting said other arm thereto, an adjustable and yieldable stop in said door frame engageable with one end of said rod for moving the actuating member in one direction 25 in a manner to rotate said arms in opposite directions about the respective pivot pins to lower said weather strip as the door is being closed, and a spring engageable adjacent its ends with the respective arms at one side of said pivot pins 30 for rotating the arms in the reverse direction to lift the weather strip and move said actuating member in the opposite direction as the door is being opened.

4. A yieldable stop for the actuating mechanism of automatic door bottoms comprising a casing adapted to be mounted in a door frame, a pressure member mounted in and relatively movable with respect to said casing, resilient means operatively related to said member and 35 casing for yieldingly urging the pressure member in one direction, and means operatively related to said member and casing for limiting the movement of the pressure member under the influence of said resilient means.

5. A yieldable stop for the actuating mechanism of automatic door bottoms comprising a cup-like casing adapted to be mounted in a door frame and having an opening formed in its bottom portion, a pressure member having a concave outer face and slidably mounted in said casing, said pressure member having a shank portion extending loosely through said opening, resilient means positioned between said member and the bottom of the casing for yieldingly urging the pressure member in one direction, and means carried by said shank portion and engageable with said casing for limiting the movement of said pressure member under the influence of said resilient means. 10 15

6. An adjustable stop for the actuating mechanism of automatic door bottoms comprising a cup-like casing adapted to be mounted in a door frame and having an opening formed in its bottom portion, a slotted pressure member adjustably mounted in said casing and having a screw-threaded shank portion extending loosely through said opening, and means outside the casing and operatively related to said pressure member and casing for adjusting the member longitudinally 20 25 of the casing.

7. An adjustable and yieldable stop for the actuating mechanism of automatic door bottoms comprising a cup-like casing adapted to be mounted in a door frame and having a plurality of oppositely disposed apertures formed in its side wall and an opening formed in its bottom portion, a concave slotted pressure member adjustably and slidably mounted in said casing and having a screw-threaded shank portion extending loosely through said opening, a spring positioned between said pressure member and the bottom of said casing for yieldingly urging the member in one direction, and means engageable with said screw-threaded shank portion and said 30 35 40 casing for adjusting the pressure member longitudinally of the casing against the action of said spring.

WILLIAM E. BALOUSEK.
